(57) **CLAIM**

The ornamental design for an auxiliary instrument panel of a vehicle, substantially as shown and described.

DESCRIPTION

FIG. 1 is a front view of an auxiliary instrument panel of a vehicle in accordance with the present design;

FIG. 2 is a rear view of the auxiliary instrument panel of a vehicle;

FIG. 3 is a left side view of the auxiliary instrument panel of a vehicle;

FIG. 4 is a right side view of the auxiliary instrument panel of a vehicle;

FIG. 5 is a top view of the auxiliary instrument panel of a vehicle;

FIG. 6 is an upward view of the auxiliary instrument panel of a vehicle; and,

FIG. 7 is a perspective view of the auxiliary instrument panel of a vehicle.

In the drawings, the broken lines depict portions of the article that form no part of the claimed design.
